UNITED STATES PATENT OFFICE

144,079

DESIGN FOR A CLOTHESPIN

Robert David Smith, Sylacauga, Ala.

Application May 29, 1945, Serial No. 119,803

Term of patent 14 years

(Cl. D17—6)

To all whom it may concern:

Be it known that I, Robert David Smith, a citizen of the United States of America, residing at Sylacauga, in the county of Talladaga and State of Alabama, have invented a new, original, and ornamental Design for a Clothespin, of which the following is a specification, reference being made to the accompanying drawing, forming a part thereof, wherein:

I claim:

The ornamental design for a clothespin, as shown.

ROBERT DAVID SMITH.
